UNITED STATES PATENT OFFICE.

PHILIP ALEXANDER MACKAY, OF NEWCASTLE, NEW SOUTH WALES,
AUSTRALIA.

REFRACTORY RECEPTACLE.

No. 799,744.

Specification of Letters Patent.

Patented Sept. 19, 1905.

Application filed April 29, 1903. Serial No. 154,795.

To all whom it may concern:

Be it known that I, PHILIP ALEXANDER MACKAY, a citizen of the United States, residing at Newcastle, in the county of Northumberland and State of New South Wales, Australia, have invented a certain new and useful Improvement in Refractory Receptacles, (Case No. 2,) of which the following is a full, clear, concise, and exact description, reference being had to the accompanying drawings, forming a part of this specification.

My invention relates to receptacles used in connection with chemical or metallurgical processes, more particularly to receptacles of refractory material, such as furnace-linings, crucibles, and retorts. Such receptacles are commonly used to hold materials which are to undergo chemical changes due to the application of heat. In many chemical operations it has been found difficult to provide such receptacles which would not be injuriously affected by the chemical reactions going on therein. These injurious effects frequently manifest themselves by a pitting or scoring of the receptacles, which finally results in the perforation of the walls thereof. While it is possible to provide substances which will not be injuriously affected by the before-mentioned reactions, such substances are otherwise unfit for the purpose of making receptacles. It has heretofore been proposed to line retorts with a substance adapted to prevent the corrosion thereof due to the attack of the chemical agencies within the retort. I have found in practice that such receptacles are much more subject to corrosion in certain localities than in others, and my invention provides for the insertion of a section of non-corrosive material at the locality or localities at which the attack of the chemical agency is most violent.

I will more particularly describe my invention by reference to the accompanying drawings, in which—

Figure 1 is a perspective view illustrating one embodiment of my invention. Fig. 2 is an end elevation of the same, and Fig. 3 is a cross-sectional view taken on line 33 of Fig. 1.

I have illustrated my invention as applied to a retort such as is commonly used in the distillation of zinc from its ores. I have found that such retorts are subject to violent scoring and corrosion largely on the lower surface thereof. The scoring or corrosion be-

gins on the lower and inner side of the retort, 55 which is finally rendered useless by a complete perforation.

I have shown a retort having a shell 4 of substantially elliptical cross-section, of which the sides 5 are placed substantially vertical 60 when in position within a furnace. The walls of the retort may desirably be made of a suitable refractory material or clay, such as mother-of-retort. These walls are of substantially the same thickness throughout. The 65 lower side of the shell is provided with an extension in the form of a shallow trough 6, adapted to retain in position a suitable insert 7, of carbon or graphite or a mixture of clay and graphite or, indeed, any non-corrosive 70 substance which will amalgamate with clay mother-of-retort and which having substantially the same coefficient of expansion and contraction will preserve a tight joint between the insert and the shell after drying 75 and burning of the retort. I have found that such an insert in the lower side of a retort used in the distillation of zinc from its ores will largely prevent the corrosion and destruction of the retort due to the attack of 80 chemical or physical reactions.

I have described my invention with particular reference to a retort which may be used for distillation purposes; but it will be apparent to those skilled in the art that it may 85 be applied to furnace-linings and crucibles which are subject to rapid corrosion in certain localities.

While I have described one particular embodiment of my invention, it will be apparent 90 that many modifications therein may be employed without departing from the spirit thereof, and I do not wish to limit myself, therefore, to the precise disclosure herein set forth; but,

Having described my invention, I claim as new and desire to secure by Letters Patent—

1. In a retort, the combination with an elliptical tubular shell of refractory material, a narrow strip of said shell at the lower part of 100 the retort being offset outwardly to form a shell-trough within the shell, and a supporting-base for the retort at the outside of the shell, and an insert of non-corrosive material in said trough, said insert having the same 105 coefficient of expansion as the material of the shell and having its upper surface continuous with the interior surface of the shell.

2. A retort consisting of the elliptical tubular shell 4, a narrow section at the lower part of said shell being offset outwardly to form a longitudinal trough within the shell, and a
5 supporting-base for the retort, an insert 7 of non-corrosible material having the same coefficient of expansion as the shell and securely fitting in said trough, the upper surface of said insert being rounded to correspond with

the inner surface of the shell and to be continuous therewith.

In witness whereof I hereunto subscribe my name this 24th day of March, A. D. 1903.

PHILIP ALEXANDER MACKAY.
